UNITED STATES PATENT OFFICE.

DONATO DI CARLO, OF PHILADELPHIA, PENNSYLVANIA.

DESIGN FOR A GRAPHOPHONE CABINET.

Application filed August 14, 1922. Serial No. 3,373. Term of patent 3½ years.

To all whom it may concern:

Be it known that I, DONATO DI CARLO, a subject of the King of Italy (having declared my intention of becoming a citizen of the United States), residing at Philadelphia, in the county of Philadelphia and State of Pennsylvania, have invented a new, original, and ornamental Design for a Graphophone Cabinet, of which the following is a specification, reference being had to the accompanying drawing, forming a part thereof, in which—

Figures 1 and 2 are perspective views looking at the front and rear respectively, of a graphophone cabinet, showing my new design.

I claim:

The ornamental design for a graphophone cabinet, as shown.

DONATO DI CARLO.
